(57) **CLAIM**

The ornamental design for a privacy screen, as shown and described.

DESCRIPTION

FIG. 1 is a front perspective view of a privacy screen, showing a first embodiment of the design; FIG. 2 is a front elevation view of the privacy screen of FIG. 1;

FIG. 3 is a right side elevation view of the privacy screen of FIG. 1, the left side being a mirror image thereof; FIG. 4 is a rear perspective view of the privacy screen of FIG. 1;

FIG. 5 is a rear elevation view of the privacy screen of FIG. 1;

FIG. 6 is a top plan view of the privacy screen of FIG. 1; FIG. 7 is a bottom perspective view of the privacy screen of FIG. 1;

FIG. 8 is a front perspective view of a privacy screen, showing a second embodiment of the design; FIG. 9 is a front elevation view of the privacy screen of FIG. 8;

FIG. 10 is a right side elevation view of the privacy screen of FIG. 8, the left side being a mirror image thereof; FIG. 11 is a rear perspective view of the privacy screen of FIG. 8;

FIG. 12 is a rear elevation view of the privacy screen of FIG. 8;

FIG. 13 is a top plan view of the privacy screen of FIG. 8; and, FIG. 14 is a bottom perspective view of the privacy screen of FIG. 8.

The dashed lines in the figures are for environmental purposes only and form no part of the claimed design.

1 Claim, 14 Drawing Sheets
